[57] CLAIM

The ornamental design for hexagonal floating live bait container, as shown and described.

DESCRIPTION

FIG. 1 is a perspective view of my hexagonal floating live bait container;

FIG. 2 is a front view thereof;

FIG. 3 is a side view thereof;

FIG. 4 is a top view thereof; and

FIG. 5 is a bottom view thereof.

The perforations are partially shown on the various surfaces for ease of illustration, but they actually cover in each instance the entire surface involved.

Fig. 1.

Fig. 2.

Fig. 4.

Fig. 3.
